[57] CLAIM

The ornamental design for a customer display or similar article, as shown and described.

DESCRIPTION

FIG. 1 is a perspective view taken from the top, front and left side of a customer display or similar article showing our new design;

FIG. 2 is a front elevational view thereof, on an enlarged scale;

FIG. 3 is a rear elevational view thereof, on an enlarged scale;

FIG. 4 is a right side elevational view thereof, on an enlarged scale;

FIG. 5 is a left side elevational view thereof, on an enlarged scale; and

FIG. 6 is a top plan view thereof, on an enlarged scale.

FIG. 1

FIG. 2

FIG. 3
